UNITED STATES PATENT OFFICE.

WILLIAM W. BRIGG, OF HOME, TENNESSEE.

IMPROVEMENT IN MACHINES FOR MAKING SHOT.

Specification forming part of Letters Patent No. 122,102, dated December 26, 1871; antedated December 6, 1871.

I, WILLIAM W. BRIGG, of Home, Greene county, Tennessee, have invented certain Improvements in Machines for Manufacturing Shot, of which the following is a specification:

My improvement consists in supplying a new article of manufacture, made of indestructible material, whereby novices as well as those skilled in the art can make shot at their homes and fire-sides with a certainty and precision not heretofore attained, and will thus inaugurate a domestic system of manufacturing capable of extension into every family of the United States, economical to those who use shot and profitable to those who may manufacture it for sale.

I am aware that portable shot-machines have been previously made; but after two or three years of experiment and effort to introduce them, they are to be found nowhere in market. They have not apparently answered the purpose intended, on account of their perishable and unreliable character as well as their mechanical defects. Being made of wood, they are warped and twisted out of a true plane by the contact of the hot lead and thus their successful operation is defeated.

It is a well-known fact that a certain and uniform temperature must be maintained in the manufacture of shot, and when the molten lead comes in contact with a substance (the machine) at a much lower temperature it is chilled and the operation of shot-making stopped. Now, by my machine, being made of iron or other metal, this difficulty is avoided, as it can be heated to the desired temperature before operations are commenced, and so prevent that chilling and cooling process referred to; thus providing the farmer, the mechanic, the gunner, and amateur sportsman with a machine, at a nominal cost, which, by its use, secures to each of them a saving of from one to five hundred per cent. or more in the cost of their ammunition.

The prevailing opinion of those who have heretofore experimented with wooden shot-machines has been that metallic ones would not operate successfully, which experience has disproved.

The operation is as follows: Take a common paper card of suitable size, perforate it with small holes, leaving the burs prominent; press the lugs B B through it; then place the lugs into the openings a a, Fig. 1; then insert the pins c

c in said lugs to prevent lateral or vertical motion of card and hopper F, except that given to the whole apparatus; sprinkle upon the burred side of card powdered sal ammoniac or borax; have ready a pail full of cold water; place the machine so prepared upon the pail, with the lugs G, Figs. I and II, on outer diameter; then have your molten lead ready, pouring a little on the card between the holes so as to fuse the sprinkled powder; then let the assistant continue to pour the lead therein while the operator has hold of the knob E, and rubbing, from the commencement to the end of the work, with a heavy stick or billet of wood upon the notches in the corrugated handle, which will impart a trembling motion to the whole machine and to the lead, causing it to disintegrate into drops, which, impinging against the water immediately below in the pail, preserves their rotundity intact; it being indispensable to success that the machine should be held perfectly loose and free in the hand and upon the outer rim of the pail, which lugs G and knob E accomplishes, to secure the vibratory and trembling motion of the machine and molten lead.

My machine is made of cast-iron or metal, in two parts, with a non-conducting handle or knob—

Figure I being a plane view without the hopper F; and Fig. II being an edge or side view, showing the hopper F in position, with lugs G B B and toothed, corrugated handle and pins c c; Fig. III being a plane view of the hopper, and Figs. IV and V being edge or side views of hopper, showing lugs, pins, and pin-holes; Fig. VI being the perforated card, marked x.

In Fig. I, a a represent openings of any size or form in base of machine, into which the rectangular or any other form of lugs B B, Figs. II, IV, and V, are inserted, and secured thereto and therein by pins c c, as seen in Figs. IV and II of hopper, &c., (the perforated card being secured between the hopper and base of machine,) which prevents any lateral or vertical motion of the hopper independent of the whole machine. D D, Figs. I and II, represent the corrugated form of handle to give additional strength thereto, in consequence of the deep notches cut or cast therein. E represents the knob. G, in dotted lines, Fig. I, and in section, Fig. II, represents

the lug to hold the machine in position on pail. The hopper F, Fig. III, is made with angular sides and ends.

Experience has demonstrated that when it is desirable to make large quantities of shot at one time it is better to have two ladles, in order that the temperature of the lead may be kept uniform, as the ladle becoming emptied cools off rapidly, as also does the lead remaining on the card when the assistant ceases pouring hot lead thereon.

I claim as my invention—

As a new article of manufacture, the shot-machine herein described, consisting of the handle D E G, hopper F suitably secured thereto, and the perforated card x, the whole constructed and arranged substantially as described.

WILLIAM W. BRIGG.
